US00D763423S

(12) **United States Design Patent**
Hewett et al.

(10) **Patent No.:** US D763,423 S
(45) **Date of Patent:** ** Aug. 9, 2016

(54) **AIR STERILIZING APPARATUS**

(71) Applicants: **Carl Gordon Hewett**, Milton Keynes (GB); **Abdel Ezbiri**, Milton Keynes (GB); **Javier Segura**, Milton Keynes (GB)

(72) Inventors: **Carl Gordon Hewett**, Keynes (GB); **Abdel Ezbiri**, Milton Keynes (GB); **Francisco Javier Segura Rius**, Milton Keynes (GB)

(73) Assignee: **Moving Sun Limited**, Milton Keynes (GB)

(**) Term: **14 Years**

(21) Appl. No.: **29/509,839**

(22) Filed: **Nov. 21, 2014**

(57) **CLAIM**

The ornamental design for an air sterilizing apparatus, as shown and described.

DESCRIPTION

FIG. 1 is a left side perspective view of an embodiment of our invention;

FIG. 2 is a left side elevational view thereof;

FIG. 3 is a top view thereof;

FIG. 4 is a front elevational view thereof;

FIG. 5 is a bottom view thereof;

FIG. 6 is a right side elevational view thereof; and,

FIG. 7 is a right side perspective view thereof.

The dashed lines immediately adjacent to the claimed areas in the drawing figures represent the boundaries of the claimed design. The dash dot lines in the figures illustrate the portions of the design that form no part of the claimed design. None of the broken lines form any part of the claimed design.

1 Claim, 3 Drawing Sheets
